(57) **CLAIM**

The ornamental design for a ridged ring as shown and described.

DESCRIPTION

FIG. 1 is a front elevation view of a ridged ring showing my design;

FIG. 2 is a right side elevation view thereof;

FIG. 3 is a top plan view thereof;

FIG. 4 is a rear elevation view thereof;

FIG. 5 is a left side elevation view thereof;

FIG. 6 is a bottom plan view thereof;

FIG. 7 is an exploded perspective view thereof shown with the two pieces that together form my design separated from each other for the purpose of clarity;

FIG. 8 is a front elevation view thereof shown with the two pieces that together form my design separated from each other for the purpose of clarity; and,

FIG. 9 is a perspective view thereof.
